To all whom it may concern:

Be it known that I, NICHOLAS WITSCH, a citizen of the United States, residing at Jersey City, in the county of Hudson and State of New Jersey, have invented and produced a new and original Design for an Ornamental Print or Pattern for Cigar-Boxes, of which the following is a specification, reference being had to the accompanying drawing, showing a part thereof.

My design is placed on a cigar-box, as shown in the drawing.

The design comprises a rectangular panel having an ornamental border, and contains an oval panel on which is depicted a field having growing tobacco-plants, cupids with

sickles, a woman seated therein holding a flambeau and supporting an open book in her lap, a horn of plenty near the woman in foreground, and the rising sun in background. ²⁰ The rectangular panel also contains a medallion upon each side of the oval frame, surmounted by a crown, and a streamer arranged lengthwise under the oval frame.

I claim—

The design for an ornamental print or pattern for cigar-boxes, substantially as shown and described.

NICHOLAS WITSCH.
